UNITED STATES PATENT OFFICE.

OSCAR J. ZIEGLER, OF FREEPORT, ILLINOIS.

DESIGN FOR AN ANCHOR FOR WINDMILL-TOWERS.

SPECIFICATION forming part of **Design No. 26,773, dated March 16, 1897.**

Application filed December 28, 1896. Serial No. 617,267. Term of patent 14 years.

To all whom it may concern:

Be it known that I, OSCAR J. ZIEGLER, a citizen of the United States, residing at Freeport, in the county of Stephenson and State of Illinois, have invented and produced a new and original Design for Anchors for Windmill-Towers, of which the following is a specification, reference being had to the accompanying drawings, forming a part thereof.

- o In the drawings, Figures 1 and 2 are respectively rear and front isometrical views of my anchor. Fig. 3 is a top plan view of the same.

An anchor embodying my invention has a leg portion V-shaped in cross-section and terminates at one end in a web-foot portion projecting outward from and at substantially right angles to the leg portion thereof.

What I claim is—

The design for an anchor for windmill-towers herein shown and described.

OSCAR J. ZIEGLER.
